PRODUCTION OF MOTOR FUEL

Maryan P. Matuszak, Bartlesville, Okla., assignor
to Phillips Petroleum Company, a corporation
of Delaware

Application January 25, 1946, Serial No. 643,222

4 Claims. (Cl. 260—683.4)

1

This application is a continuation-in-part of my copending application Serial No. 467,872, filed December 4, 1942, which is now Patent 2,399,368, granted April 30, 1946. The invention represents an improvement over conventional processes of producing motor-fuel hydrocarbons by hydrofluoric acid alkylation of isoparaffins with olefins and/or alkyl fluorides, which have been described in the prior art. It is distinguished from these processes in that the alkylation is effected with a 1-olefin in substantially prehydrofluorinated form, with any other olefin being utilized as such, without first being prehydrofluorinated. It is based in part upon the surprising and unexpected discovery that a positive advantage resides in hydrofluorinating a 1-olefin prior to utilization for alkylation of an isoparaffin, in that the resulting alkylate is superior in octane rating to that obtained by direct alkylation with the 1-olefin as such; whereas substantially only disadvantages reside in similar prehydrofluorination of olefins other than 1-olefins. In one specific embodiment, the invention is an improved process of manufacturing motor-fuel paraffins from butanes, whereby normal butane is dehydrogenated, the resulting butene-1 is isolated and is used in substantially hydrofluorinated form to alkylate isobutane in the presence of hydrofluoric acid, the butene-2 resulting from the dehydrogenation is simultaneously used substantially as such to alkylate isobutane, and the resulting alkylates are withdrawn together as a motor-fuel product of high octane rating.

An object of this invention is to produce paraffin hydrocarbons boiling in the motor fuel range and of high octane number.

Another object of my invention is to produce paraffin hydrocarbons of high octane number from a mixture of low-boiling olefin hydrocarbons.

Still another object of my invention is to produce paraffin hydrocarbons from a mixture of low-boiling alpha and beta olefins.

Further objects and advantages of my invention will become apparent, to one skilled in the art, from the accompanying disclosure and discussion.

One specific embodiment, which may serve as an illustrative example of the invention, is depicted by the drawing, which is a schematic flow-diagram showing a preferred arrangement of apparatus and steps suitable for practicing this embodiment. For simplicity, the drawing refers to manufacture of motor-fuel hydrocarbons from hydrocarbons having four carbon atoms per molecule, which are preferred, but it will be understood that substantially equivalent hydrocarbons having more carbon atoms per molecule may be utilized similarly.

2

A mixture of butanes brought into the system by inlet 1 is fractionated in fractionator 2 into an overhead fraction rich in isobutane and into a bottom fraction rich in normal butane. The isobutane fraction is passed into conduit 3, being controllably augmented or diminished, as may be desired, through valve 4 in a connection with an outside storage of isobutane, not shown. The normal butane fraction is passed through conduit 5 to dehydrogenator 6, being controllably augmented or diminished, as may be desired, through valve 7 in a connection with an outside source of normal butane, not shown.

In dehydrogenator 6, normal butane is catalytically dehydrogenated substantially into normal butylenes, preferably by the action of a dehydrogenation catalyst comprising chromium oxide. Inasmuch as catalytic dehydrogenating of paraffins is well known, it need not be described in detail. In present industrial practice, such dehydrogenation converts approximately 25 to 40 per cent of the normal butane per pass, yielding normal butylenes with a selectivity of approximately 70 to 85 per cent.

The resulting dehydrogenation mixture is passed through conduit 8 to separation means represented by fractionator 9, which in practice generally comprises several fractional-distillation and/or extractive-distillation columns. Low-boiling gaseous by-products are withdrawn, as through outlet 10. Butadiene preferably also is withdrawn, as through outlet 11. Undehydrogenated normal butane is recycled through conduit 12 to dehydrogenator 6. Butene-2 is passed through conduit 13. Butene-1 is passed through conduit 14 to hydrofluorinator 15.

In hydrofluorinator 15, butene-1 is substantially hydrofluorinated to butyl fluoride. Great care must be exercised in the hydrofluorination to minimize consumption of butene-1 to products other than butyl fluoride, and certain specific features of this invention are concerned primarily with this fact. It is essential for optimum results to avoid having present in the hydrofluorination zone a distinct liquid phase rich in hydrofluoric acid, inasmuch as a liquid hydrofluoric acid phase acts catalytically to promote such undesired side reactions as polymerization of the butene-1 and alkylation of isoparaffins, when present. These reactions, if initiated by a trace of liquid hydrofluoric acid phase, have a pronounced tendency to pyramid or "run away" because they liberate additional hydrofluoric acid from butyl fluoride already formed, thereby augmenting the amount of undesirably catalytically active liquid hydrofluoric acid phase present. When run-away side reactions occur, introduction of hydrofluoric acid

into the hydrofluorination zone must be discontinued, until all liquid hydrofluoric acid phase has disappeared by reaction and by dissolution in the hydrocarbon phase. Inasmuch as uniformity of ultimate product and minimization of process changes or controls to compensate for operational difficulties are highly advantageous and desirable, it is clear that run-away side reactions in the hydrofluorination are strongly disadvantageous and are not lightly to be tolerated.

Although the occurrence of run-away side reactions in the hydrofluorination zone can be substantially avoided by conducting the hydrofluorination in gaseous phase, and although gas-phase hydrofluorination is not to be considered as being excluded from the broadest scope of this invention, it is usually relatively economically advantageous to employ liquid-phase hydrofluorination, in view of the smaller size of equipment that is then adequate for maintaining a desired throughput. To achieve this objective without any possibility of a liquid hydrofluoric acid phase being present, it is an advantageous specific feature of this invention to introduce the hydrofluoric acid into hydrofluorinator 15 in the form of a saturated solution in the isoparaffin that is subsequently to be alkylated. In addition to serving as a carrier or solvent for the hydrofluoric acid, the isoparaffin dilutes the butene-1 in the hydrofluorination zone, thereby preferentially disfavoring polymerization, inasmuch as the rate of polymerization is proportional to the second power of the olefin concentration, whereas the rate of hydrofluorination is proportional to only the first power of the olefin concentration. Most commonly, and preferably, the isoparaffin is liquefied isobutane, but a heavier isoparaffin, such as isopentane, may be used.

In the embodiment illustrated, isobutane is conducted through conduit 3 to saturator 22. Simultaneously concentrated, or substantially anhydrous, hydrofluoric acid is introduced into saturator 22 through inlet 23. In saturator 22, the isobutane becomes saturated with the hydrofluoric acid. Various means of contacting or mixing to achieve this objective can be used; they need not be described in detail, inasmuch as they can be readily provided by those skilled in the art. However, it may be mentioned that the isobutane is introduced into saturator 22 at a somewhat elevated temperature, in order to increase the solubility of hydrofluoric acid in it; the most satisfactory temperature range is approximately 120 to 180° F., which may be obtained directly, without heat exchange, in the isobutane fraction from fractionator 2. At the middle temperature of this range, 150° F., which is preferred, the solubility of anhydrous hydrofluoric acid in isobutane appears to be approximately 2.1 per cent by weight; however, the solubility of hydrofluoric acid of the purity ordinarily available at present for commercial alkylation may be appreciably less than this value, apparently chiefly because of a small content of water, so that at times the solubility may be so low as approximately 1.5 per cent, especially when the solubility is somewhat decreased by the presence of normal butane in the isobutane. The value of 2.1 per cent corresponds to a mol ratio of isobutane to hydrogen fluoride of approximately 16:1. If desired, the temperature of the influent isobutane may be adjusted so that approximately this preferred ratio is maintained; however, other ratios are operative and may be used, especially the higher ratios obtained at lower temperatures,

thereby disfavoring polymerization and favoring alkylation in the subsequent alkylation step.

From saturator 22, the mixture of isobutane and hydrofluoric acid is passed through conduit 24 to separator 25, in which it is separated into two liquid phases. The lower, hydrofluoric acid-rich phase is recycled through conduit 26 to saturator 22. The upper, isobutane-rich phase is passed through conduit 27 to hydrofluorinator 15.

In hydrofluorinator 15, this isobutane phase, which is substantially saturated with hydrofluoric acid, is intimately mixed with butene-1 from conduit 14, whereupon substantial hydrofluorination of the butene-1 is effected. The proportion of butene-1 introduced into the hydrofluorination zone is preferably such that the mol ratio of ingoing hydrofluoric acid to ingoing butene-1 is approximately 1:1. Although advantageously higher values for this ratio are desirable, especially those in the range of 1.3:1 to 1.6:1, inasmuch as the rate of hydrofluorination is directly proportional to the concentration of hydrofluoric acid, this particular ratio has been found to represent the approximate optimum compromise among the several reaction-affecting factors or variables involved; however, lower values, down to approximately 0.5:1, are also usefully operative, though the hydrofluorination then proceeds somewhat relatively slowly and is necessarily relatively less nearly complete. Inasmuch as the rate of hydrofluorination increases with increase in temperature, the temperature is preferably somewhat elevated, but it should not be so high as to interfere by substantially lowering the thermodynamic ceiling. The temperature established by the influent isobutane, which is at approximately 120 to 180° F., is advantageously convenient, so that no special heat-exchange means for hydrofluorinator 15 need be provided; this temperature is somewhat increased, by approximately 10° F. or so, by liberation of the heat of hydrofluorination. The reaction time, or time of residence of the reaction mixture in hydrofluorinator 15, may vary considerably, depending on the temperature and the reactant concentrations; times in the range of 4 to 40 minutes have been used with satisfaction, and ordinarily sufficient hydrofluorination occurs under the preferred conditions in 5 to 10 minutes. It will be understood that the hydrofluorination of butene-1 need not proceed to completion, or to the thermodynamic equilibrium, and that only the substantial hydrofluorination that occurs within an industrially feasible reaction time is desirably effected.

From hydrofluorinator 15, the effluent reaction mixture is passed through conduit 30 to alkylator 31. Preferably, this mixture is cooled, as in cooler 32, to a temperature of 90 to 110° F., inasmuch as the subsequent alkylation is exothermic. However, cooler 32 is not always necessary, as when adequate cooling for the subsequent alkylation is provided in alkylator 31, which in present commercial practice is ordinarily designed for the somewhat relatively more highly exothermic alkylation with olefins.

Although, in some modifications of this invention, the alkylation taking place in alkylator 31, may be substantially limited to the isobutane, the butyl fluoride, and the unhydrofluorinated butene-1 in the effluent from hydrofluorinator 15, in most preferred modifications the butene-2 in conduit 13 is simultaneously introduced into alkylator 31. Ordinarily, such butene-2, which

if desired may have associated with it an appreciable proportion of isobutylene added as through inlet 33 to enhance the octane rating of the ultimate alkylate, is approximately twice as large in amount as the original butene-1; consequently, the mol ratio of isobutane to the total butylenes plus butyl fluoride is reduced to the approximate value of 5:1, which in present commercial practice is preferred as being economically optimum. When such olefins other than butene-1 would reduce this mol ratio below 5:1, additional isobutane may be added, as through inlet 34, but ordinarily it is relatively more advantageous to increase correspondingly the isobutane going to saturator 22. Hydrofluoric acid required as alkylating catalyst is introduced through inlet 35.

Except for the differences already indicated hereinbefore the alkylation and product-recovery steps may be along substantially conventional lines. Briefly, alkylation of isobutane with butyl fluoride and butylenes occurs in alkylator 31 under conditions substantially like those well known in the art, with liberation of hydrofluoric acid from the butyl fluoride. The resulting effluent reaction mixture is passed through conduit 36 to separator 37. The separated used-acid or catalyst phase is recycled in part through conduit 38 to alkylator 31 and is passed in part through conduit 39 to acid fractionator 40 for purification, with tar or acid-soluble oil being removed through outlet 41 and with purified hydrofluoric acid and a minor proportion of isobutane being passed to saturator 22 through conduit 42. When the hydrofluoric acid in the alkylator builds up too much, part of the used acid may be passed to saturator 22 through conduit 50. The hydrocarbon phase from separator 37 is passed through conduit 43 to fractionator 44, usually a system of fractional-distillation columns, from which a major fraction comprising isobutane and a minor proportion of hydrofluoric acid is returned through conduit 45 to saturator 22. It is worthy of note that the recovered hydrofluoric acid and the recovered unalkylated isobutane, in conduits 42 and 45, are passed to saturator 22 instead of to alkylator 31, in conformity with the over-all requirements of the process; however, if desired, means, not shown, may be readily provided for passing part of either or both of these materials to alkylator 31. Tar or heavy alkylate is withdrawn through outlet 46, and motor fuel is withdrawn as the principal product through outlet 47.

The resulting motor fuel is substantially superior in octane rating to that obtainable without the improvements provided by this invention.

It will be understood that various conformably applicable known means for improving alkylation in general, or similarly for improving the alkylate, such as, for example, a defluorination step to decrease traces of organic fluorine-containing by-products, may be utilized in connection with the process of the present invention; for example, the defluorination means described in Frey Patent 2,347,945, or in my copending application Serial No. 602,247, filed June 29, 1945, may be applied to the material in conduit 43. The gist of the present invention resides in one or more of the steps and conditions herein set forth for obtaining an alkylate of enhanced octane rating by virtue of substantial prehydrofluorination of substantially only a 1-olefin, which in most instances is specifically butene-1 but in other instances may comprise pentene-1 or even propylene. The presence of other olefins in the prehydrofluorination zone represented by hydrofluori-

nator 15, such as, for example, isobutylene and/or butene-2, is undesirable and disadvantageous, inasmuch as no correspondingly additional enhancement in octane rating of the ultimate alkylate is thereby obtained; inasmuch as they disfavor hydrofluorination of the 1-olefin, as by decreasing the concentration of hydrofluoric acid in this zone; and inasmuch as they undergo polymerization relatively more easily than butene-1, so that subjecting them to prehydrofluorination results in a net decrease in the yield of the ultimate alkylate. Consequently, although the ultimate alkylate in many cases may contain, in the form of a blend or composite mixture, alkylation products from these or other olefins other than 1-olefins that may be formed in a common alkylation zone or alternatively and ordinarily relatively less economically in an alkylation zone different from that in which the prehydrofluorinated 1-olefin is used, prehydrofluorination in accordance with the principles of the present invention is most advantageously applied to only 1-olefins, inasmuch as thereby the contribution of the 1-olefin to the quality of the ultimate alkylate is enhanced to the fullest possible extent consistent with the other conditions of manufacture. The actual octane rating of the ultimate alkylate depends to a considerable degree on the proportions of the various olefins going into its manufacture; for example, the relative octane rating of the hydrofluoric acid alkylate from isobutane and isobutylene is largest, from isobutane and butene-2 is intermediate, and from isobutane and butene-1 is smallest. By way of comparison, it may be said that, by the practice of this invention, the octane rating for the alkylate from isobutane and butene-1 is increased substantially to the intermediate value characteristic for that from isobutane and butene-2. The mechanism or theoretical explanation of this effect is not completely understood at present, but it may be significant that both butene-1 and butene-2 undergo hydrofluorination to substantially the same principal product, secondary butyl fluoride. From a theoretical point of view, therefore, a particular advantage of excluding butene-2 from the hydrofluorination of butene-1, in addition to the general advantages already indicated hereinbefore, appears to be one of avoiding an unnecessarily high concentration of this butyl fluoride, inasmuch as, in accordance with the principle of mass action, the presence of this butyl fluoride militates against union of the butene-1 with the hydrofluoric acid.

In addition to data subsequently presented, the data in Table I represent some illustrative results obtained in a pilot-plant investigation directed to determining the optimum conditions for the hydrofluorination step. The hydrocarbon feed was forced through a silica-gel drier and through a copper-coil pre-heater into a reactor, which in most of the runs was a 1470-ml. copper-plated steel reactor having a 1750-R. P. M. 2.5-inch turbo-mixer. Commercial anhydrous hydrofluoric acid was simultaneously forced into the reactor. Feed and effluent samples, the latter after being free from dissolved hydrofluoric acid by extraction with water, were analyzed by low-temperature fractional distillation, supplemented by sulfuric acid determination of olefin (Matuszak, Ind. and Eng. Chem., Anal. Ed., 10, 354-360 (1938)). Hydrofluoric acid in the effluent was determined by extraction with water and subsequent titration of the extract with standard sodium hydroxide.

¹ Reactor was 700-ml. brass-lined steel vessel with 1750-R. P. M. 4-blade impeller.

² Determined by weathering 70-80 ml. snap sample.

These data illustrate to a helpful extent the influences of such operating variables as temperature, reaction time, feed composition, and mol ratio of hydrofluoric acid to butene-1. The phenomenon describable as "run-away alkylation" occurred in run-periods 476-2 and 476-3, as was evidenced by the large proportion of heavy products formed.

Several continuous pilot-plant runs were made for the hydrofluoric acid alkylation of isobutane with butene-1, with and without prehydroflu-

orination of the butene-1. The alkylator was a 1470-ml. copper-plated steel reactor provided with a 2.5-inch turbo-mixer, whose shaft bearing and packing box were protected from contact with liquid hydrofluoric acid by the incoming feed. In the prehydrofluorination runs, the total effluent from the hydrofluorinator, which was a 700-ml. brass-lined steel vessel having a 1750-R. P. M. 4-blade impeller, was passed through a cooling coil directly to the alkylator. The data obtained are summarized in Table II.

It may be noted that the runs with prehydrofluorination of the butene-1 yielded alkylates markedly superior to those obtained without prehydrofluorination, as is indicated by the relatively high ASTM octane numbers. With one exception, the proportion of isoctane (2,2,4-trimethylpentane) formed in these runs was considerably higher than in the runs without prehydrofluorination, and the consumption of isobutane relative to original butene-1 was also higher. In the exceptional run, run 473, "run-away alkylation" occurred during the prehydrofluorination in period 5, as is indicated by the high content of hydrofluoric acid in the effluent, thereby accounting for the relatively poor alkylate yield, isobutane consumption, isoctane proportion, and octane number, as compared with those obtained in runs 469 and 484. The relatively poor results of this run emphasized the desirability of avoiding a liquid hydrofluoric acid phase during the prehydrofluorination, which as a specific objective is simply and positively attainable in the practice of this invention as set forth hereinbefore, particularly in the discussion of the flow-diagram.

It will be appreciated that various modifications of my invention can be practiced without departing from the spirit or scope of the disclosure and teachings, or without departing from the scope of the claims.

I claim:

1. An improved process for converting a butane mixture into higher-boiling paraffin hydrocarbons, which comprises separating from a butane mixture normal butane and isobutane, saturating said isobutane as a liquid with hydrogen fluoride, subjecting said normal butane to dehydrogenation under conditions such as to produce therefrom butene-1 and butene-2, separating from effluents of said dehydrogenation butene-1 and butene-2 so produced as separate fractions, admixing said butene-1 fraction with said hydrogen fluoride-saturated liquid isobutane fraction in an amount such that the mol ratio of hydrogen fluoride to added butene-1 is between about 1:1 and 1.6:1 and maintaining said admixture at a temperature between about 120 and 180° F. for a time in the range of about 4 to 40 minutes to react butene-1 and hydrogen fluoride, admixing with effluents of said treatment said butene-2 and addi-

tional liquid concentrated hydrogen fluoride in an amount sufficient to act as an alkylation catalyst and intimately admixing said materials under alkylation conditions for a time sufficient to effect an alkylation of said isobutane, and recovering from effluents of said alkylation higher-boiling paraffin hydrocarbons so produced.

5 2. An improved process for converting a mixture of butene-1 and butene-2 to higher-boiling paraffin hydrocarbons, which comprises separating butene-2 from said mixture, converting residual butene-1 to butyl fluoride, passing said butene-2 and said butyl fluoride to an alkylation zone and reacting same therein with a low-boiling isoparaffin hydrocarbon under alkylation conditions and in the presence of a hydrofluoric acid alkylation catalyst, and recovering as a product of the process a paraffinic hydrocarbon fraction comprising paraffin hydrocarbons produced by said alkylation.

10 3. The process of claim 2 wherein said low-boiling isoparaffin is isobutane.

4. An improved process for converting a mixture of low-boiling normal 1-olefin and normal 2-olefin to higher-boiling paraffin hydrocarbons, which comprises separating said normal 2-olefin from said mixture, converting residual 1-olefin to an alkyl fluoride, passing said 2-olefin and said alkyl fluoride to an alkylation zone and reacting same therein with a low-boiling isoparaffin hydrocarbon under alkylation conditions and in the presence of a hydrofluoric acid alkylation catalyst, and recovering as a product of the process a paraffinic hydrocarbon fraction comprising paraffin hydrocarbons produced by said alkylation.
